GLOBE CLOCK

Raymond R. Dupler, Toledo, Ohio

Application February 18, 1939, Serial No. 257,054

4 Claims. (Cl. 58—44)

This invention relates to terrestrial globe clocks in which a globe containing a map of the world has associated with it clock mechanism for indicating the time in various parts of the world.

5 An object is to produce a new and improved terrestrial globe clock of the above character in which the time indicator is arranged inside of the globe but when the inside of the globe is illuminated the time indicator is visible from the outside, so that the globe is unobstructed and can be readily examined but in which the clock feature may be visible as desired and will readily display the corresponding time in different parts of the world.

10 15 Another object is to produce a globe clock of the above character wherein the clock mechanism is disposed within the globe and which is mounted together with the time indicating device in a simple and efficient manner.

20 Another object is to produce a globe clock of the above character with the time indicating device inside of the globe and with the globe so mounted that it can be turned for examination of different parts thereof without affecting the clock mechanism so that the relative arrangement of the globe and time indicating device will not be altered.

25 Other objects and advantages will hereinafter appear and for purposes of illustration but not of limitation, an embodiment of the invention is shown on the accompanying drawings in which

30 Figure 1 is a side elevation of a terrestrial globe clock with a portion thereof broken away to show a time indicating device disposed on the inside of the globe;

35 Figure 2 is a view partly in cross section, the section being taken on a vertical plane which approximately bisects the globe shown in Figure 1;

40 Figure 3 is an enlarged view of the clock driving mechanism and associated parts, partly in cross-section, the section being taken on approximately the same plane as the view shown in Figure 2;

45 Figure 4 is a transverse sectional view with some of the parts removed showing the gear drive for the time indicating device; and the section being taken approximately along the line 4—4 in Figure 3 and looking in the direction of the arrows;

50 Figure 5 is a transverse sectional view substantially on the line 5—5 of Figure 3.

The illustrated embodiment of the invention comprises a globe clock consisting of a glass sphere 10 made up of two parts fitting together in overlapping relationship. Suitably mounted on

the outside of the globe is a map of the world 11 which may be of paper or may be painted thereon or otherwise suitably displayed in such manner that a lamp on the inside of the globe will illuminate the outside thereof. As will hereinafter appear, the globe 10 is mounted on a base 12 to which leads wires 13 having a connecting plug 14 at the outer end. Switches 15 and 16 on the base 12 control the clock operating motor and the lamp respectively as will hereinafter appear.

10 The lower section of the globe 10 is formed with a rectangular opening 17 which fits over a similarly shaped projection 18 on an annular block 19. The block 19 is rotatable in a recess 20 formed in the upper part of the base 12. It will be observed that the inside of the base 12 is hollow and extending through the upper wall thereof for turning movements therein is a tube 21, the upper end of which is screw-threaded into a platform member 22. The tube is provided with a 20 polygonal flange 23 which abuts against the underside of the upper wall of the base and depending therefrom is an extension 24 carrying the three vertically spaced contact rings 25 with which brushes 26 carried by spring arms 27 engage. The spring arms are suitably connected to the switches 15 and 16 in the manner indicated in Figure 2. The wires from the contact rings 25 extend upwardly through the extension 24 and tube 21 and thence through a tube 28 30 from which wires 29 are connected for operating an electric motor 30 and other connections lead to a base 31 of any suitable type on which an electric lamp 32 is mounted. Mounted on the upper end of the tube 28 is a wire bracket 33 35 which extends on both sides of the lamp 32 and provides a support for a connecting device 34 which holds the two sections of the globe 10 against separation. The bracket 33 is provided at its upper extremity with a screw threaded projection which extends through an opening in the upper section of the globe 10. The connecting device 34 threadedly engages this projection and functions to retain the upper section of the globe in proper position. The connecting device 34 extends through an opening in the upper section of the globe in such manner that the bracket 33 can turn when the globe is turned or rotated upon its base 12.

40 The platform member 22 has a relatively wide 50 platform part 35, a reduced connecting part 36 which embraces the tube 21 and a lower part 37 which cooperates with the block 19 in clamping the globe in position, a suitable gasket 38 being interposed between the part 37 and globe. A set 55

screw 38 extends through the reduced part 36 and bears against the tube 21 for securing the parts against relative movement.

The platform part 35 is formed with an annular recess 40 in which fits a ring 41 for turning movement thereon. Secured to the upper face of the ring 41 are a plurality of spaced rods or arms 42 which incline upwardly and outwardly and clamped on the upper end of each of the arms 42 are brackets 43 respectively. The brackets 43 are integral with and extend inwardly from the lower edge of an annulus or ring 44 of glass or other suitable translucent or transparent material. The ring 44 is vertically disposed with the walls thereof substantially parallel to the axis of the globe 10 and is arranged midway between the opposite ends thereof. As shown in Figure 1, the outer surface of the ring 44 is formed with calibrations 45, numbers and other indicia designating the time. It will be apparent that when the lamp 32 is lighted, the indicia 45 will be visible from the outside of the globe, the arrangement being such that the corresponding time in different parts of the world will be indicated. For example, by examining the globe, the time in New York can be readily ascertained and by turning the globe, the time in Tokio is also readily observed. Ordinarily, the map is divided by lines of longitude into the different time zones to enable the time in different places to be readily observed.

Formed on the inside of the ring 41 is an annular series of gear teeth 46 with which a pinion 47 meshes. The pinion 47 is mounted on a vertical shaft 54 having bearing within a box 55 integral with a plate 48. A suitable clutch 49 is interposed between the parts of the shaft 54 to enable the ring 41 and the time indicating ring 44 to be turned or adjusted independently of the upper portion of the shaft 54. Mounted on the upper end of the shaft 44 is a worm wheel 49 with which a worm 50 meshes. The worm 50 is fixed to a horizontal shaft 50 forming an extension of the armature of the motor 30. The motor 30 and associated parts are of the ordinary sixty cycle type used for electric clocks and since these motors are well-known to those skilled in this art, further description and illustration thereof is not considered necessary.

50 The plate 48 is in screw-threaded engagement with the lower end of the tube 28 and is secured to the platform part 35 and is held in spaced relation thereto by bolts 51 which extend through the opening in the ring 41. The motor 30 is secured 55 to the plate 48 by a suitable supporting bracket 52.

From the above description it will be apparent that the electric motor 30 through the connections described imparts turning movement to the 50 ring 41, the arms 42 turning the glass time indicating ring 44 relative to the globe 10 so that the indicia thereon will appear through the walls of the globe to be viewed from the outside when the lamp 32 is lighted. When it is desired to inspect 55 different parts of the globe, the same may be turned, and when the globe is turned the motor, time indicating device and associated parts turn with it. In the event it is necessary to make an

adjustment in the relative position of the time indicating ring 44, the connecting device 34 is removed so that the upper section of the globe can be removed, whereupon the time indicating ring may be turned as desired in view of the 5 clutch 47 above described.

It will thus be apparent that I have provided an exceedingly simple arrangement which enables the globe to be used in the usual manner, but which, in addition, provides a clock, the parts of 10 which do not in any way interfere with the surface of the map. The simple construction and arrangement enable the parts to be manufactured and assembled at a relatively low cost.

Numerous changes in details of construction, 15 arrangement and operation may be effected without departing from the spirit of the invention, especially as defined in the appended claims.

What I claim is:

1. A clock comprising a base, a terrestrial 20 translucent globe mounted on said base for turning movements, a support secured to said globe and projecting inside thereof, a ring rotatably mounted on said support within said globe, a device within said globe having marks designating 25 the time, a support for said device on said ring, a plate secured to said support and spaced therefrom, an electric clock mechanism mounted upon said plate, an operative driving connection between said clock mechanism and said ring, and a 30 lamp within said globe carried by said plate.

2. A clock comprising a base, a terrestrial translucent globe mounted on said base for turning movements, a support secured to said globe and projecting inside thereof, a ring rotatably mounted on said support within said globe, a glass ring within said globe in close juxtaposition to the inner wall of said globe, a plate secured to said support and spaced therefrom, an electric clock mechanism mounted upon said plate, an operative driving connection between said clock mechanism and said ring, and a 40 globe carried by said plate.

3. In combination, a supporting base, a hollow terrestrial translucent globe rotatably mounted 45 thereon, a platform within said globe, clock mechanism mounted on said platform, an annular member associated with said platform and adapted to be rotated by said clock mechanism, a transparent annular indicia bearing ring supported by and rotatable with said annular member, and means for illuminating the interior of 50 said globe.

4. A clock assembly comprising a support, a hollow translucent terrestrial globe rotatably secured to said support, a platform within said globe and secured against rotation with respect to said globe, time controlled mechanism mounted on said platform, gear means associated with said platform and rotatable with respect thereto by means of said time controlled mechanism, a time indicia bearing circular member supported by and rotatable with said gear means, whereby the rotation of said indicia bearing member with respect to said globe is dependent upon said time 65 controlled mechanism.

RAYMOND R. DUPLER.
